UNITED STATES PATENT OFFICE.

LEWIS B. DOMAN, OF ELBRIDGE, NEW YORK, ASSIGNOR, BY MESNE ASSIGNMENTS, TO
AUTOPIANO COMPANY, A CORPORATION OF NEW YORK.

WEB-GUIDING DEVICE.

1,094,428.

Specification of Letters Patent. Patented Apr. 28, 1914.

Application filed January 2, 1909. Serial No. 470,431.

To all whom it may concern:

Be it known that I, LEWIS B. DOMAN, of Elbridge, in the county of Onondaga, in the State of New York, have invented new and useful Improvements in Web-Guiding Devices, of which the following, taken in connection with the accompanying drawings, is a full, clear, and exact description.

This invention relates to certain improvements in web guiding devices of the class set forth in my pending applications No. 422,970, filed March 24th, 1908, and No. 461,931, filed November 10th, 1908, the latter resulting in Patent 939,897, Nov. 9, 1909, and although it is specifically adapted for maintaining normal alinement or registration between the music sheet and tracker bar, it is equally useful in guiding any traveling web or sheet relatively to some other part with which it is associated. In this class of apparatus the normal relation between the traveling sheet or web and tracker bar is automatically maintained through the medium of suitable air ports 25 acting with the music sheet or with suitable valves controlled by such music sheet, together with the pneumatic or pneumatics communicating with said ports and brought into action by the abnormal shifting of either web or tracker bar to restore normal 30 relation between such parts.

The width of the same or different webs or sheets frequently varies, either by cutting or by expansion or contraction, and the essential object of my present invention and those previously referred to is to provide a suitable means for simultaneously adjusting the ports and guide fingers (when the latter are used) toward and from each other 40 to conform to the different widths of the web or sheet with which such ports coact, so that the sensitiveness of the pneumatic for restoring normal relation between the music sheet or web and tracker bar may be 45 maintained.

Other objects and uses relating to specific parts of the mechanism will be brought out in the following description.

In the drawings—Figure 1 is a front elevation of a portion of a music box, showing the tracker bar, and my invention applied

thereto, the music sheet being shown by dotted lines, while the restoring pneumatic is shown partly in section. Fig. 2 is an enlarged top plan, partly in section and partly broken away, of the tracker bar showing the adjustable ports and guide fingers for the music sheet. Fig. 3 is a rear elevation of the tracker bar, showing the adjusting means for the ports and guide fingers. Fig. 4 is a top plan, partly in section and partly broken away, of a modified form of my invention, in which the adjustable ports open at the face of the tracker bar and are adjustable relatively thereto, the guide fingers being omitted.

The apparatus shown in Figs. 1 to 3 inclusive comprises a tracker bar —1—, valve ports —2—, guide fingers —3—, and adjustable supports —4— for the guide fingers and valve ports, said guide fingers carrying suitable valves —5— normally closing the ports —2—. These ports are connected by conduits —6— to a suitable pneumatic —7— having a central partition —8—, dividing the pneumatic —7— into compartments 70 9 and 9' to which the conduits —6— are respectively connected. The movable partition —8— of the pneumatic —7— is normally balanced by equal air pressure at 80 opposite sides thereof in the air chambers 9 and 9' when normal relation exists between the tracker bar —1— and the traveling web or sheet —a—. The movable member 8 is connected by a link —10— to the tracker 85 bar —1— to impart motion from the partition —8— to said tracker bar, when the pneumatic balance of the partition —8— is disturbed by the opening of one or the other of the ports —2— due to the relative shifting of the music sheet or tracker bar by the action of the edge of the music sheet upon one or the other of the guide fingers —3—. I have found it more convenient to shift the tracker bar to maintain normal relation between it and the music sheet, and for this purpose have connected the movable portion of pneumatic —7— directly to said tracker bar, although it is evident that a similar connection may be made with the 90 music sheet support for shifting the music sheet relatively to the tracker bar, if desired.

The tracker bar —1— is adjustable lengthwise upon suitable supports —11— forming, in this instance, the sides of the music-box of a self playing instrument, said tracker bar being provided with a plurality of, in this instance two, elongated openings or recesses —12—, preferably in proximity with the longitudinal edges of the music sheet when moving in its normal line of travel 10 across the face of the tracker bar. The guide fingers —3— of which there are, in this instance, two are also located at the opposite edges of the music sheet and are centrally pivoted at —13— to inwardly projecting ears upon the adjustable brackets —4— at the rear of the tracker bar, the front ends of the guide fingers —3— being extended through the recesses or openings —12—, and a short distance beyond the 20 front face of the tracker bar, where they are adapted to contact with the opposite longitudinal edges of the music sheet for guiding the latter in its travel across the face of the tracker bar. The portion of the fingers projecting through the apertures or recesses —12— are of considerably less width than the length of the openings to allow for ample adjustment of the fingers lengthwise of the bar to conform to the different widths 25 of the web or music sheet. The front end of the fingers —3— are provided with inwardly projecting shoulders or paper rests —14—, having their front faces coincident with that of the tracker bar for supporting 30 the edges of the sheet and thereby preventing depression of the edge of the sheet into the recesses 12 while traveling across the face of the tracker bar. The opposite or rear ends of the guide fingers —3— are provided with the valves —5— normally closing 35 the ports —2—, which otherwise would open to the atmosphere, said fingers being spring tensioned by springs —16— to yieldingly hold the valves closed. The brackets —4— carrying the respective ports —2— and guide fingers —3— are, as previously stated, mounted upon the tracker bar —1— and are adjustable toward and from each other lengthwise of the bar by means of a 40 cam or double crank arm —17—, (Fig. 3) and links —18— and —19— connected respectively to the opposite brackets —4—, the double crank arm being, in this instance, secured to a pivoted spindle —20— (Fig. 2) 45 which is journaled in the tracker bar, and is provided on its front end with a hand piece or knob —21— by which the lever may be turned upon its axis to simultaneously shift brackets —4— and parts carried there- 50 by in opposite directions. Each bracket —4— is slidably held in place by a screw —22—, which is passed through an elongated slot in the foot of the bracket to permit the longitudinal adjustment previously

described, the portion of the screw which 65 passes through the slot being surrounded by a roller of sufficient length to prevent binding of the head of the screw against the bracket, said roller being shown in section at the right of Fig. 2. The tracker bar is 70 provided with the usual ducts —23— which are connected by pipes —23'— in the usual manner to the primary pneumatic of the sound producing action, not shown. The chambers —9— and —9'— of the pneumatic 75 —7— are connected through comparatively small apertures —25— with a duct —26— in the movable portion —8—, which duct in turn is connected by a flexible pipe or conduit —27— to the usual exhaust bellows 80 or wind inducing device, not shown.

In Fig. —4— I have shown the conduit —6— as attached to suitable ducts —28—, which in turn are mounted in brackets —4— and have their front ends extending through 85 the openings or recesses —12— and terminating in a plane coincident with the face of tracker bar and across which the edges of the music sheet are adapted to travel. The mouths of the ducts —28— therefore constitute guide openings, which under normal conditions are covered by the edges of the music sheet, and being connected to the chambers —9 and 9'— of the pneumatic —10—, it is evident that if one of the ports 90 95 is uncovered by the shifting of the music sheet or tracker bar the movable member of the pneumatic —7— will be brought into action to restore normal relations between such parts, it being understood that the 100 tracker bar of the device shown in Fig. —4— is connected to the movable portion —8— in the same manner as shown in Fig. —1—.

In operation the tracker bar and music sheet are normally adjusted so that the perforations of the music sheet will register with corresponding ducts —23— in the tracker bar, the guide fingers —3— being adjusted to lightly engage the opposite longitudinal edges of the music sheet in which 110 position the valves —5— normally close ports —2—, thereby causing an equal air tension in the air chambers 9 and 9', to normally balance the partition —8—. If for any reason the traveling music sheet should 115 shift laterally relative to the tracker bar sufficient to move one of the fingers —3— from its normal position, the corresponding valve —5— would be opened thereby, allowing the air to pass through tube —6— into the corresponding chamber 9 or 9', thus increasing the air pressure in such chamber and causing the movable portion —8— to shift toward the opposite side of the pneumatic and correspondingly shift the tracker bar into 120 125 normal relation with the music sheet. After normal relation between the tracker bar and music sheet has been restored, the movable

partition will remain in its shifted position by reason of the equality of air tension in the opposite chambers —9— and —9'— until again shifted by abnormal relation between 5 said bar and sheet. If the web or music sheet is of greater or less width than the distance between the contact portions of the guide fingers —3—, the latter may be readily adjusted into close engagement with the 10 edges of the music sheet by simply turning the knob —21— in one direction or another, thereby shifting the fingers in opposite directions an equal distance, which enables the sheet to maintain its normal line of travel 15 with reference to the ducts of the tracker bar. In like manner the guide openings or ducts —28— may be adjusted to bring both of the said openings directly under the edges of the web or music sheet and if either the 20 music sheet or tracker bar should shift laterally sufficient to uncover one of the ports, the air pressure in the corresponding chamber of the pneumatic —7— would be increased causing the movable portions of the 25 pneumatic to restore normal relations between the tracker bar and music sheet.

What I claim is:—

1. In a web guiding device, valves having 30 movable fingers engaging the edges of and adapted to be actuated by the web when the latter shifts from its normal line of travel, pneumatic means brought into action by the movement of either of said valves for restoring the web to its normal line of travel, and 35 separate means for adjusting said fingers for different widths of webs.

2. In a web guiding device, a bar, a pair of supports relatively adjustable on said bar, fingers movably mounted on the supports engaging 40 the longitudinal edges of the web and adapted to be operated thereby when the web shifts in either direction from its normal line of travel, and means controlled by said fingers for restoring the web to its normal line of travel.

3. In combination with a tracker bar and 50 perforated music sheet of a self-playing musical instrument, valves having movable fingers contacting with opposite edges of the sheet and adapted to be operated by abnormal shifting of the sheet, means controlled by said valves for maintaining normal relation between the sheet and tracker bar, and separate means for adjusting the movable 55 fingers to conform to different widths of sheets.

4. In combination with a tracker bar and 60 a perforated music sheet of a self-playing musical instrument, contact members adjustably mounted on the bar and contacting with opposite edges of the sheet, pneumatic means controlled by said members for maintaining normal relation between the music sheet and tracker bar, and separate means

for simultaneously adjusting both members 65 lengthwise of the bar.

5. The combination with the tracker bar and a perforated music sheet of a self-playing musical instrument, of a pair of simultaneously adjustable contact fingers mounted upon the tracker bar to engage the longitudinal edges of the music sheet and adapted to be moved by the shifting of the sheet in either direction from its normal line of travel, and means controlled by the movement of said fingers operable to restore normal relations between the sheet and the tracker bar.

6. In combination with a tracker bar and perforated music sheet of a self-playing 80 musical instrument, a movable guide member having a portion thereof underlying the sheet and another portion contacting with the edge thereof, and pneumatic means controlled by said member for maintaining normal relation between the sheet and tracker bar.

7. In combination with a tracker bar and traveling music sheet of a self-playing musical instrument, levers having portions 90 thereof contacting with the opposite edges of the sheet and adapted to be operated by abnormal shifting of the sheet, pneumatic means controlled by said levers for maintaining normal relation between the sheet 95 and tracker bar, and separate means for simultaneously adjusting the levers to conform to different widths of sheets.

8. In combination with a tracker bar and traveling music sheet of a self-playing 100 musical instrument, mechanism for automatically maintaining normal relation between the music sheet and tracker bar comprising a pair of exhaust chambers and a movable partition between said chambers 105 normally balanced by equal air tension therein, connections between the partition and tracker bar, and separate atmosphere ports relatively adjustable on the tracker bar, and each connected by an unobstructed 110 passage directly to one of the exhaust chambers.

9. In a device of the class described, the combination of a tracker, means for supporting the tracker so that it can move laterally, 115 and means including valves having fingers on the tracker for engaging the sheet and keeping the tracker in register therewith, said fingers having projecting lugs thereon to support the sheet.

10. In a device of the class described, the combination of a tracker, bearings for supporting the same so as to permit a free lateral play thereof, and means including valves having sheet engaging fingers carried by the 125 tracker for keeping the tracker in register with the sheet.

11. In a device of the class described, the

combination of a tracker, means for supporting the same so that it can move laterally, sheet engaging fingers carried by the tracker, and means for adjusting the sheet engaging fingers so that they will always be equally distant from the center of the tracker.

In witness whereof I have hereunto set my hand this 12 day of December, 1908.

LEWIS B. DOMAN.
